UNITED STATES PATENT OFFICE.

FRANK CHROBAK, OF ORIENT, PENNSYLVANIA.

TOILET ARTICLE.

1,397,403.

Specification of Letters Patent. Patented Nov. 15, 1921.

Application filed June 20, 1921. Serial No. 479,062.

To all whom it may concern:

Be it known that I, FRANK CHROBAK, a citizen of Poland, residing at Orient, in the county of Fayette and State of Pennsylvania, have invented certain new and useful Improvements in Toilet Articles, of which the following is a specification.

This invention relates to certain new and useful improvements in toilet articles and has particular reference to a combination toilet article embodying a brush and mirror frame adapted to be secured altogether and provide a housing for a comb or manicure implements.

The primary object of the invention resides in the provision of a toilet article wherein brush and mirror elements are detachably connected together by manually releasable tension devices so that the parts

20 may be separated and used as desired.

With the above general objects in view and others that will appear as the nature of the invention is better understood, the same consists in the novel form, combination and arrangement of parts hereinafter more fully described, shown in the accompanying drawing and claimed.

In the drawing, wherein like reference characters designate corresponding parts 30 throughout the several views,

Figure 1 is a plan view of the inner face of the mirror element of the toilet article showing a nail file confined therein.

Fig. 2 is a plan view of the back face of 35 the brush element showing a comb and shoe button hook disposed therein,

Fig. 3 is a side elevational view, partly in section of the mirror and brush elements secured together and illustrating the tension 40 latch for holding the parts in assembled relation,

Fig. 4 is a cross sectional view taken on line IV—IV of Fig. 3 showing the pivoted hook connection between the mirror and 45 brush elements, and

Fig. 5 is a cross sectional view taken on line V—V of Fig. 1 showing the nail file confined within the mirror element.

Referring more in detail to the accompanying drawing and particularly to Figs. 1, 2 and 4 there is illustrated a toilet article embodying a mirror frame 1 and a brush frame 2, the outer edges of the opposed faces of the mirror and brush frames being 55 provided with contacting flanges 3 as shown in Fig. 4 to form a casing or housing be-

tween the mirror and brush frames as illustrated.

The two frames are of the conventional form embodying enlarged head portions and 60 reduced handle portions, the mirror frame 1 having a glass 4 secured in the enlarged end thereof as shown in Figs. 1 and 4, while the neck portion connecting the head and handle portions is provided with opposed 65 overhanging ledges 5 for engagement with the blade 6 of a nail file that is disposed within the handle as shown in Fig. 1.

The brush frame 2 has a bristle portion 7 upon the outer face thereof and a headed 70 pin 8 secured centrally of the inner face of the head portion for confining a comb 9 as shown in Fig. 2. The handle portion of the brush frame may receive any convenient 75 toilet article such as a button hook 10.

The connection between the mirror and brush frames embodies pivot hook, and tension latch devices, one side flange 3 of the brush frame 2 adjacent the opposite ends thereof being provided with openings covered by face plates 11 having a central aperture 12 for the reception of pivot hooks 13 carried by adjacent portion on the flanges 3 of the mirror frame 1, these elements being clearly shown in Figs. 1 and 2. The 80 tension latch device for locking the mirror and brush frames in assembled relation embodies a pair of plates 14 secured to the other flanges 3 of the mirror frame 1 and having central apertures 15 therein. The 85 flanges 3 of the brush frame 2 opposite the face plates 11 are cut away as at 16 upon the face thereof, such cut away portions communicating with lateral openings 17. A cup-shaped frame 18 is disposed within the 95 cut away portion 16 and has a latch 19 pivoted therein and tensioned as at 20 to cause the latch head 19' to be projected through the opening 15 in the plate 14 and so retained. To release the lever 19 from 100 engagement with the plate 14 and against the tension of the spring 20, the finger lever 21 pivoted within the cup-shaped member 18 and projecting through the side openings 17 as shown in Fig. 3 has a link connection 105 22 with the latch lever 19, so that operation of the finger lever 21 will shift the latch lever 19 to disengage the latch lever head 19' from the plate 14, operation of the latch devices at each end of the article permitting 110 separation thereof.

From the above detail description of the

device, it is believed that the construction and operation thereof will at once be apparent, it being noted that the channel construction of the mirror and other elements 5 provides a casing or receptacle for toilet or manicure articles while the tension latch connections between the mirror and brush elements securely hold the parts in assembled relation.

10 While there is herein shown and described the preferred embodiment of the present invention, it is nevertheless to be understood that minor changes may be made therein without departing from the spirit and scope 15 of the invention as claimed.

What is claimed as new is:—

1. A toilet article comprising mirror and brush frames, each frame having opposed marginal flanges, one of said frames having 20 openings in the marginal flange at one side thereof, hook members carried by one of the marginal flanges of the other frame for reception in said openings, and tension latch devices connecting the other adjacent marginal flanges.

2. A toilet article comprising mirror and brush frames, each frame having opposed marginal flanges, one of said frames having 25

openings in the marginal flange at one side thereof, hook members carried by one of the 30 marginal flanges of the other frame for reception in said openings, tension latch devices connecting the other adjacent marginal flanges, said tension latch devices including keeper openings formed in the side 35 flange of one frame, and tension latch levers pivotally mounted in the adjacent flange of the other frame.

3. A toilet article comprising mirror and brush frames, each frame having opposed 40 marginal flanges, one of said frames having openings in the marginal flange at one side thereof, hook members carried by one of the marginal flanges of the other frame for reception in said openings, tension latch devices connecting the other adjacent marginal flanges, said tension latch devices including keeper openings formed in the side 45 flange of one frame, latch levers pivotally mounted in the adjacent flange of the other 50 frame, a spring associated with each latch lever for holding the same under tension, and finger levers for operating the tensioned latch levers.

In testimony whereof I affix my signature. 55
FRANK CHROBAK.
